(57) **ABSTRACT**

A control panel for an appliance defines a display direction and includes a printed circuit board defining a first surface, a second surface opposite the first surface along the display direction, and a through hole passing through the printed circuit board from the first surface to the second surface. A console cover is mounted to the first surface of the printed circuit board, a standoff feature is positioned between the console cover and the printed circuit board to create a localized gap between the console cover and the printed circuit board, a retention feature engages the second surface to retain the printed circuit board against the console cover, and an electronic component mounted to the printed circuit board and having an electrical contact that extends through the through hole where it forms a connection joint that is positioned within the localized gap.

MOUNTING ASSEMBLY FOR A PRINTED CIRCUIT BOARD WITHIN AN APPLIANCE CONTROL PANEL

FIELD OF THE INVENTION

The present subject matter relates generally to control panels for appliances, and more particularly to features for mounting printed circuit boards within appliance control panels.

BACKGROUND OF THE INVENTION

Appliances frequently include doors for closing, insulating, concealing, or otherwise providing selective access to cavities or chambers of the appliance. These doors typically include an inner and outer door that are separated by an air gap which may be filled with fiberglass or insulating foam, e.g., for thermal insulation, sound dampening, etc. In order to provide a user with information regarding the appliance operation, e.g., such as a status of an operating cycle or an indication that a cycle is complete, status indicators are often positioned on the outer door of the appliance such that they are visible to a user of the appliance. In addition, or alternatively, appliances such as dishwasher appliance may include control panels that are integrated into the top of the dishwasher door, e.g., to minimize features on the outer door and provide a clean look.

Conventional appliance control panels use through hole connectors for mounting various electronic components to a printed circuit board. These through hole connectors are electrical harness headers that pass through a hole in the printed circuit board and are soldered on the opposite side. Alternative constructions use a surface mount connector where the leads are bent 90 degrees and do not go through the board, but these connections often have poor mechanical retention, larger board footprint, higher costs, and poor availability relative to through hole connections.

Notably, when through hole connectors are used with directly adhered capacitive touch controls, a recess typically needs to be formed on the cover to provide clearance for the protrusions where the soldered connections are made. These recesses can cause read through defects on the appearance surface of the control cover, which is undesirable and creates user dissatisfaction.

Accordingly, an appliance having an improved door and control panel assembly would be useful. More specifically, a control panel for an appliance having a compact design with through hole connectors and improved appearance would be particularly beneficial.

BRIEF DESCRIPTION OF THE INVENTION

Aspects and advantages of the invention will be set forth in part in the following description, or may be obvious from the description, or may be learned through practice of the invention.

In one exemplary embodiment, a control panel for an appliance is provided. The control panel defines a display direction and includes a printed circuit board defining a first surface, a second surface opposite the first surface along the display direction, and a through hole passing through the printed circuit board from the first surface to the second surface, a console cover mounted to the first surface of the printed circuit board, a standoff feature positioned between the console cover and the printed circuit board to create a localized gap between the console cover and the printed

2

circuit board, a retention feature that engages the second surface to retain the printed circuit board against the console cover, and an electronic component mounted to the printed circuit board and having an electrical contact that extends through the through hole, wherein a distal end of the electrical contact forms a connection joint that is positioned within the localized gap between the printed circuit board and the console cover.

In another exemplary embodiment, a dishwasher appliance defining a vertical direction, a lateral direction, and a transverse direction is provided. The dishwasher appliance includes a wash tub positioned within a cabinet and defining a wash chamber, a door pivotally mounted to the cabinet to provide selective access to the wash chamber, and a control panel mounted on the door and defining a display direction. The control panel includes a printed circuit board defining a first surface, a second surface opposite the first surface along the display direction, and a through hole passing through the printed circuit board from the first surface to the second surface, a console cover mounted to the first surface of the printed circuit board, a standoff feature positioned between the console cover and the printed circuit board to create a localized gap between the console cover and the printed circuit board, a retention feature that engages the second surface to retain the printed circuit board against the console cover, and an electronic component mounted to the printed circuit board and having an electrical contact that extends through the through hole, wherein a distal end of the electrical contact forms a connection joint that is positioned within the localized gap between the printed circuit board and the console cover.

These and other features, aspects and advantages of the present invention will become better understood with reference to the following description and appended claims. The accompanying drawings, which are incorporated in and constitute a part of this specification, illustrate embodiments of the invention and, together with the description, serve to explain the principles of the invention.

BRIEF DESCRIPTION OF THE DRAWINGS

A full and enabling disclosure of the present invention, including the best mode thereof, directed to one of ordinary skill in the art, is set forth in the specification, which makes reference to the appended figures.

FIG. 1 provides a perspective view of a dishwasher appliance, including a dishwasher door according to exemplary embodiments of the present disclosure.

FIG. 2 provides a cross-sectional side view of the exemplary dishwashing appliance of FIG. 1.

FIG. 3 provides a close-up perspective view of a control panel of the exemplary dishwasher door of FIG. 1 according to exemplary embodiments of the present disclosure.

FIG. 4 provides a top perspective view of the exemplary control panel of FIG. 3 according to exemplary embodiments of the present disclosure.

FIG. 5 provides a cross-sectional of the exemplary control panel of FIG. 3 taken along Line 5-5 of FIG. 4 according to exemplary embodiments of the present disclosure.

FIG. 6 provides a bottom view of the exemplary control panel of FIG. 3 according to exemplary embodiments of the present disclosure.

FIG. 7 provides a perspective view of the exemplary control panel of FIG. 3 with the printed circuit board removed to illustrate a console cover according to exemplary embodiments of the present disclosure.

FIG. 8 provides a side, cross-sectional view of the exemplary console cover of FIG. 7 according to exemplary embodiments of the present disclosure.

FIG. 9 provides a perspective view of a standoff feature of the exemplary console cover of FIG. 7 according to exemplary embodiments of the present disclosure.

FIG. 10 provides a perspective view of a console cover according to exemplary embodiments of the present disclosure.

FIG. 11 provides a side, cross-sectional view of the exemplary console cover of FIG. 10 according to exemplary embodiments of the present disclosure.

Repeat use of reference characters in the present specification and drawings is intended to represent the same or analogous features or elements of the present invention.

DETAILED DESCRIPTION

Reference now will be made in detail to embodiments of the invention, one or more examples of which are illustrated in the drawings. Each example is provided by way of explanation of the invention, not limitation of the invention. In fact, it will be apparent to those skilled in the art that various modifications and variations can be made in the present invention without departing from the scope or spirit of the invention. For instance, features illustrated or described as part of one embodiment can be used with another embodiment to yield a still further embodiment. Thus, it is intended that the present invention covers such modifications and variations as come within the scope of the appended claims and their equivalents.

As used herein, the terms "first," "second," and "third" may be used interchangeably to distinguish one component from another and are not intended to signify location or importance of the individual components. The terms "includes" and "including" are intended to be inclusive in a manner similar to the term "comprising." Similarly, the term "or" is generally intended to be inclusive (i.e., "A or B" is intended to mean "A or B or both"). The term "at least one of" in the context of, e.g., "at least one of A, B, and C" refers to only A, only B, only C, or any combination of A, B, and C. In addition, here and throughout the specification and claims, range limitations may be combined and/or interchanged. Such ranges are identified and include all the sub-ranges contained therein unless context or language indicates otherwise. For example, all ranges disclosed herein are inclusive of the endpoints, and the endpoints are independently combinable with each other. The singular forms "a," "an," and "the" include plural references unless the context clearly dictates otherwise.

Approximating language, as used herein throughout the specification and claims, may be applied to modify any quantitative representation that could permissibly vary without resulting in a change in the basic function to which it is related. Accordingly, a value modified by a term or terms, such as "generally," "about," "approximately," and "substantially," are not to be limited to the precise value specified. In at least some instances, the approximating language may correspond to the precision of an instrument for measuring the value, or the precision of the methods or machines for constructing or manufacturing the components and/or systems. For example, the approximating language may refer to being within a 10 percent margin, i.e., including values within ten percent greater or less than the stated value. In this regard, for example, when used in the context of an angle or direction, such terms include within ten degrees greater or less than the stated angle or direction, e.g.,

"generally vertical" includes forming an angle of up to ten degrees in any direction, e.g., clockwise or counterclockwise, with the vertical direction V.

The word "exemplary" is used herein to mean "serving as an example, instance, or illustration." In addition, references to "an embodiment" or "one embodiment" does not necessarily refer to the same embodiment, although it may. Any implementation described herein as "exemplary" or "an embodiment" is not necessarily to be construed as preferred or advantageous over other implementations. Moreover, each example is provided by way of explanation of the invention, not limitation of the invention. In fact, it will be apparent to those skilled in the art that various modifications and variations can be made in the present invention without departing from the scope of the invention. For instance, features illustrated or described as part of one embodiment can be used with another embodiment to yield a still further embodiment. Thus, it is intended that the present invention covers such modifications and variations as come within the scope of the appended claims and their equivalents.

FIGS. 1 and 2 depict an exemplary domestic dishwasher or dishwashing appliance 100 that may be configured in accordance with aspects of the present disclosure. For the particular embodiment of FIGS. 1 and 2, the dishwasher 100 includes a cabinet 102 having a tub 104 therein that defines a wash chamber 106. As shown, tub 104 extends between a top 107 and a bottom 108 along a vertical direction V, between a pair of side walls 110 along a lateral direction L, and between a front side 111 and a rear side 112 along a transverse direction T. Each of the vertical direction V, lateral direction L, and transverse direction T are mutually orthogonal to one another.

The tub 104 includes a front opening 114 and a door 116 hinged at its bottom for movement between a normally closed vertical position (shown in FIG. 2), wherein the wash chamber 106 is sealed shut for washing operation, and a horizontal open position for loading and unloading of articles from the dishwasher 100. According to exemplary embodiments, dishwasher 100 further includes a door closure mechanism or assembly 118 that is used to lock and unlock door 116 for accessing and sealing wash chamber 106.

As illustrated in FIG. 2, tub side walls 110 may accommodate a plurality of rack assemblies. More specifically, guide rails 120 may be mounted to side walls 110 for supporting a lower rack assembly 122, a middle rack assembly 124, and an upper rack assembly 126. As illustrated, upper rack assembly 126 is positioned at a top portion of wash chamber 106 above middle rack assembly 124, which is positioned above lower rack assembly 122 along the vertical direction V. Each rack assembly 122, 124, 126 is adapted for movement between an extended loading position (not shown) in which the rack is substantially positioned outside the wash chamber 106, and a retracted position (shown in FIGS. 1 and 2) in which the rack is located inside the wash chamber 106. This is facilitated, for example, by rollers 128 mounted onto rack assemblies 122, 124, 126, respectively. Although a guide rails 120 and rollers 128 are illustrated herein as facilitating movement of the respective rack assemblies 122, 124, 126, it should be appreciated that any suitable sliding mechanism or member may be used according to alternative embodiments.

Some or all of the rack assemblies 122, 124, 126 are fabricated into lattice structures including a plurality of wires or elongated members 130 (for clarity of illustration, not all elongated members making up rack assemblies 122, 124, 126 are shown in FIG. 2). In this regard, rack assem-

biles 122, 124, 126 are generally configured for supporting articles within wash chamber 106 while allowing a flow of wash fluid to reach and impinge on those articles (e.g., during a cleaning or rinsing cycle). According to another exemplary embodiment, a silverware basket (not shown) may be removably attached to a rack assembly (e.g., lower rack assembly 122) for placement of silverware, utensils, and the like, that are otherwise too small to be accommodated by rack 122.

Dishwasher 100 further includes a plurality of spray assemblies for urging a flow of water or wash fluid onto the articles placed within wash chamber 106. More specifically, as illustrated in FIG. 2, dishwasher 100 includes a lower spray arm assembly 134 disposed in a lower region 136 of wash chamber 106 and above a sump 138 so as to rotate in relatively close proximity to lower rack assembly 122. Similarly, a mid-level spray arm assembly 140 is located in an upper region of wash chamber 106 and may be located below and in close proximity to middle rack assembly 124. In this regard, mid-level spray arm assembly 140 may generally be configured for urging a flow of wash fluid up through middle rack assembly 124 and upper rack assembly 126. Additionally, an upper spray assembly 142 may be located above upper rack assembly 126 along the vertical direction V. In this manner, upper spray assembly 142 may be configured for urging or cascading a flow of wash fluid downward over rack assemblies 122, 124, and 126. As further illustrated in FIG. 2, upper rack assembly 126 may further define an integral spray manifold 144, which is generally configured for urging a flow of wash fluid substantially upward along the vertical direction V through upper rack assembly 126.

The various spray assemblies and manifolds described herein may be part of a fluid distribution system or fluid circulation assembly 150 for circulating water and wash fluid in the tub 104. More specifically, fluid circulation assembly 150 includes a pump 152 for circulating water or wash fluid (e.g., detergent, water, or rinse aid) in the tub 104. Pump 152 may be located within sump 138 or within a machinery compartment located below sump 138 of tub 104, as generally recognized in the art. Fluid circulation assembly 150 may include one or more fluid conduits or circulation piping for directing water or wash fluid from pump 152 to the various spray assemblies and manifolds. For example, as illustrated in FIG. 2, a primary supply conduit 154 may extend from pump 152, along rear 112 of tub 104 along the vertical direction V to supply wash fluid throughout wash chamber 106.

As illustrated, primary supply conduit 154 is used to supply wash fluid to one or more spray assemblies (e.g., to mid-level spray arm assembly 140 and upper spray assembly 142). However, it should be appreciated that according to alternative embodiments, any other suitable plumbing configuration may be used to supply wash fluid throughout the various spray manifolds and assemblies described herein. For example, according to another exemplary embodiment, primary supply conduit 154 could be used to provide wash fluid to mid-level spray arm assembly 140 and a dedicated secondary supply conduit (not shown) could be utilized to provide wash fluid to upper spray assembly 142. Other plumbing configurations may be used for providing wash fluid to the various spray devices and manifolds at any location within dishwasher appliance 100.

Each spray arm assembly 134, 140, 142, integral spray manifold 144, or other spray device may include an arrangement of discharge ports or orifices for directing wash fluid received from pump 152 onto dishes or other articles located

in wash chamber 106. The arrangement of the discharge ports, also referred to as jets, apertures, or orifices, may provide a rotational force by virtue of wash fluid flowing through the discharge ports. Alternatively, spray arm assemblies 134, 140, 142 may be motor-driven, or may operate using any other suitable drive mechanism. Spray manifolds and assemblies may also be stationary. The resultant movement of the spray arm assemblies 134, 140, 142 and the spray from fixed manifolds provides coverage of dishes and other dishwasher contents with a washing spray. Other configurations of spray assemblies may be used as well. For example, dishwasher 100 may have additional spray assemblies for cleaning silverware, for scouring casserole dishes, for spraying pots and pans, for cleaning bottles, etc. One skilled in the art will appreciate that the embodiments discussed herein are used for the purpose of explanation only and are not limitations of the present subject matter.

In operation, pump 152 draws wash fluid in from sump 138 and pumps it to a diverter assembly 156 (e.g., which may be positioned within sump 138 of dishwasher appliance 100). Diverter assembly 156 may include a diverter disk (not shown) disposed within a diverter chamber 158 for selectively distributing the wash fluid to the spray arm assemblies 134, 140, 142 or other spray manifolds or devices. For example, the diverter disk may have a plurality of apertures that are configured to align with one or more outlet ports (not shown) at the top of diverter chamber 158. In this manner, the diverter disk may be selectively rotated to provide wash fluid to the desired spray device.

According to an exemplary embodiment, diverter assembly 156 is configured for selectively distributing the flow of wash fluid from pump 152 to various fluid supply conduits, only some of which are illustrated in FIG. 2 for clarity. More specifically, diverter assembly 156 may include four outlet ports (not shown) for supplying wash fluid to a first conduit for rotating lower spray arm assembly 134 in the clockwise direction, a second conduit for rotating lower spray arm assembly 134 in the counter-clockwise direction, a third conduit for spraying an auxiliary rack such as the silverware rack, and a fourth conduit for supply mid-level or upper spray assemblies 140, 142 (e.g., such as primary supply conduit 154).

The dishwasher 100 is further equipped with a controller 160 to regulate operation of the dishwasher 100. The controller 160 may include one or more memory devices and one or more microprocessors, such as general or special purpose microprocessors operable to execute programming instructions or micro-control code associated with a cleaning cycle. The memory may represent random access memory such as DRAM, or read only memory such as ROM or FLASH. In one embodiment, the processor executes programming instructions stored in memory. The memory may be a separate component from the processor or may be included onboard within the processor. Alternatively, controller 160 may be constructed without using a microprocessor (e.g., using a combination of discrete analog or digital logic circuitry, such as switches, amplifiers, integrators, comparators, flip-flops, AND gates, and the like) to perform control functionality instead of relying upon software.

The controller 160 may be positioned in a variety of locations throughout dishwasher 100. In the illustrated embodiment, the controller 160 may be located within a control panel area 162 of door 116, as shown in FIGS. 1 and 2. In such an embodiment, input/output ("I/O") signals may be routed between the control system and various operational components of dishwasher 100 along wiring harnesses that may be routed through the bottom of door 116. Typi-

cally, the controller 160 includes a user interface panel 164 through which a user may select various operational features and modes and monitor progress of the dishwasher 100. In one embodiment, the user interface 164 may represent a general purpose I/O (“GPIO”) device or functional block. In certain embodiments, the user interface 164 includes input components 166, such as one or more of a variety of electrical, mechanical or electro-mechanical input devices including rotary dials, push buttons, and touch pads. The user interface 164 may further include one or more display components 168, such as a digital display device or one or more indicator light assemblies designed to provide operational feedback to a user. The user interface 164 may be in communication with the controller 160 via one or more signal lines or shared communication busses.

It should be appreciated that the invention is not limited to any particular style, model, or configuration of dishwasher 100. The exemplary embodiment depicted in FIGS. 1 and 2 is for illustrative purposes only. For example, different locations may be provided for user interface 164, different configurations may be provided for rack assemblies 122, 124, 126, different spray arm assemblies 134, 140, 142 and spray manifold configurations may be used, and other differences may be applied while remaining within the scope of the present subject matter. Moreover, aspects of the present subject matter may be applied to other appliances as well, such as refrigerators, ovens, microwaves, etc.

Referring now generally to FIGS. 3 through 7, a door assembly 200 will be described according to exemplary embodiments of the present subject matter. For example, door assembly 200 may be used as door 116 of dishwashing appliance 100. Alternatively, door assembly 200 may be used on any other suitable residential or commercial appliance. As described herein, door assembly 200 may share a coordinate system with dishwashing appliance 100, e.g., when door assembly 200 is in the closed position (e.g., as shown in FIG. 2). Specifically, door assembly 200 may define a vertical direction V, a lateral direction L, and a transverse direction T. Therefore, these directions may be used herein to refer to features of door assembly 200 and its various components and sub-assemblies. Referring briefly again to FIGS. 1 and 2, in the normally closed position, door assembly 200 (illustrated for example as door 116) extends from a top end or top edge 202 to a bottom end or bottom edge 204 along the vertical direction V; from a front end 206 to a rear end 208 along the transverse direction T; and between two lateral ends 210 along the lateral direction L.

As best illustrated in FIG. 3, door assembly 200 may include a door frame 212 that is formed from one or more exterior panels. In general, these exterior panels of door frame define an interior chamber 214 of door assembly 200. For example, door assembly 200 generally includes an inner door panel 216 and an outer door panel 218 which are spaced apart from each other along the transverse direction T to define a door gap or interior chamber 214 of door assembly 200 therebetween. For instance, outer door panel 218 may be positioned at or proximal to the front end 206 (i.e., distal to the rear end 208) and inner door panel 216 may be positioned at or proximal to the rear end 208 (i.e., distal to the front end 206).

According to exemplary embodiments, inner door panel 216 and outer door panel 218 may be panels that are stamped from stainless steel. Alternatively, inner door panel 216 and outer door panel 218 may be formed from any other suitably rigid material, such as thermoformed plastic, other metals, etc. In general, inner door panel 216 and outer door panel 218 may be assembled in any suitable manner. In addition,

inner door panel 216 and outer door panel 218 may be secured together using any suitable mechanical fastener, welding, snap-fit mechanisms, etc. In addition, it should be appreciated that an insulating material (not shown), such as fiberglass or foam insulation, may be positioned within interior chamber 214 to provide thermal and/or sound insulation to dishwashing appliance 100.

As illustrated, door assembly 200 may generally include a control panel 220 that is mounted on door assembly 200 and is generally configured for facilitating user interaction with the dishwasher 100. In this regard, for example, control panel 220 (e.g., which may correspond to control panel 162 from FIG. 1) may be in direct operative communication with controller 160 of dishwasher 100, such that user inputs via control panel 220 may be directly used to regulate operation of various components of dishwasher 100.

According to the illustrated embodiment, control panel 220 may be positioned on top edge 202 of door assembly 200 along the vertical direction V. Thus, e.g., control panel 220 may be partially hidden below a countertop when dishwashing appliance 100 is installed below the countertop and door 116 (e.g., door assembly 200) is closed. Accordingly, dishwashing appliance 100 may be referred to as a “top control dishwashing appliance.” However, it should be appreciated that aspects of the present subject matter may be used with dishwashing appliances having other configurations or any other suitable appliance. For example, control panel 220 may be mounted on a front end 206 of door assembly 200 or may be mounted directly to an appliance cabinet or other suitable support structure for regulating the operation of any suitable appliance.

According to exemplary embodiments of the present subject matter, control panel 220 may generally define a display direction (e.g., identified generally by reference numeral 222). In general, display direction 222 may refer to the direction along which a user typically views control panel 220. For example, for a top control dishwashing appliance, the display direction 222 may generally extend normal to top edge 202 of door assembly 200. In other words, display direction 222 extends along the vertical direction V when door assembly 200 is in the closed position and along the transverse direction T when door assembly 200 is in the fully open position. By contrast, for front display dishwashing appliances, the display direction 222 may extend out a front end 206 door assembly 200. It should be appreciated that the directional orientations provided herein are only intended to facilitate discussion of aspects of the present subject matter, e.g., to describe the relative positioning of various components of control panel 220. However, it should be appreciated that these directional orientations may vary depending on the construction of the door assembly while remaining within the scope of the present subject matter.

Referring now specifically to FIGS. 5 and 6, control panel 220 may generally include a user interface board or printed circuit board 230 that may generally be configured for supporting controller 160 and various other control inputs or outputs of dishwashing appliance 100. More specifically, as understood by one of ordinary skill in the art, printed circuit board 230 may include or be operably coupled to one or more user inputs (e.g., user inputs 166) for receiving user input and/or to one or more displays or indicators (e.g., display components 168) for providing user notifications, e.g., by illuminating indicators to indicate cycles or operating status.

According to the illustrated embodiment, printed circuit board 230 generally extends along a horizontal plane (e.g., along the lateral direction L and the transverse direction T)

within door assembly 200. More specifically, printed circuit board 230 may extend along the lateral direction L within door assembly 200, e.g., at least partially between lateral ends 210. In addition, printed circuit board 230 may generally extend along the transverse direction T between front end 206 and rear end 208 of door assembly 200. According to the illustrated embodiment, printed circuit board 230 generally defines a first surface or a top surface 232 that extends within a horizontal plane when door assembly 200 is in the closed position. In addition, printed circuit board 230 defines a second surface or a bottom surface 234 that is opposite top surface 232 along the display direction 222.

According to the illustrated embodiment, door assembly 200 may further include a plurality of light sources (not shown) that are mounted to top surface 232 of printed circuit board 230 for selectively generating light. In this regard, light sources may be configured for illuminating indicators, control inputs, or other features on control panel 220. These light sources may include any suitable number, type, configuration, and orientation of light sources mounted at any suitable location to illuminate status indicators or buttons in any suitable colors, sizes, patterns, etc.

In other words, light sources may be provided as any suitable number, type, position, and configuration of electrical light source(s), using any suitable light technology and illuminating in any suitable color. For example, according to the illustrated embodiment, light sources may include one or more light emitting diodes (LEDs), which may each illuminate in a single color (e.g., white LEDs), or which may each illuminate in multiple colors (e.g., multi-color or RGB LEDs) depending on the control signal from controller 160.

However, it should be appreciated that according to alternative embodiments, light sources may include any other suitable traditional light bulbs or sources, such as halogen bulbs, fluorescent bulbs, incandescent bulbs, glow bars, a fiber light source, etc. Moreover, light sources may be operably coupled (e.g., electrically coupled) to printed circuit board 230, another suitable control board, and/or controller 160 (FIG. 2). Activation or illumination of light sources may be generally controlled by a printed circuit board 230 or controller 160 (e.g., to indicate a user input, state of the dishwasher appliance, state of the wash cycle, or any other relevant information to a user).

As best illustrated in FIG. 5, control panel 220 may generally include a console cover 240 that is mounted to printed circuit board 230. In this regard, for example, console cover 240 may be any suitable electrically insulated and opaque material that is mounted on top surface 232 of printed circuit board 230, e.g., to serve as a rigid support to facilitate user interaction with control panel 220. For example, according to the illustrated embodiment, console cover 240 may define a bottom surface 242 that is mounted in direct contact against top surface 232 of printed circuit board 230, as explained in more detail below.

In this regard, bottom surface 242 and top surface 232 may be substantially planar surfaces that extend along the horizontal direction when door assembly 200 is in the closed position. According to alternative embodiments, printed circuit board 230 could also be mounted with adhesive between the top surface 232 of printed circuit board 230 and bottom surface 242 of console cover 240, may be spaced at a set distance, etc. In addition, console cover 240 may define a top surface 244 that is positioned opposite a bottom surface 242 along the display direction 222 (e.g., along the vertical direction V when door assembly 200 is in the closed position).

In addition, an overlay panel 250 (see FIG. 4) may be mounted on top of console cover 240. More specifically, overlay panel 250 may include a bottom surface that is seated directly against top surface 244 of console cover 240. In addition, overlay panel 250 may include a top surface 252 that is directly interacted with by a user of dishwasher appliance 100. In general, overlay panel 250 may be any suitable panel for dead fronting control panel 220 to a user of dishwasher appliance 100. As used herein, the term “dead front” and the like is generally intended to refer to portions of a control panel which may be used as indicators, buttons, interactive control surfaces, or other user-interaction features without exposing the user to the operating side of the equipment or live parts and connections, i.e., lights, electrical connections, etc. According to exemplary embodiments, overlay panel 250 may further include a diffusion layer that is printed or applied to the bottom surface of overlay panel 250 to help facilitate distribution of light.

For example, overlay panel 250 may include a transparent or translucent body and an opaque masking material 254 that is selectively printed on top surface 252 (or bottom surface) of the translucent body to define one or more indicator zones 256 (e.g., corresponding to user inputs 166 or other indicators) and/or other illuminated features on control panel 220. In this regard, an opaque masking material 254 may be deposited on the translucent body, may be applied using an adhesive, or may be applied in any other manner to define any suitable number, size, and configuration of illuminated features. These illuminated features may be shapes or include other forms such as symbols, words, etc. that are visible on control panel 220. More specifically, when the light sources are energized, indicator zones 256 that correspond to the user inputs 166 or other indicators may be illuminated. Thus, the dead fronted top surface 252 may be the surfaces that are contacted for controlling dishwasher appliance 100 or which may be illuminated for purposes of indicating operating status or other conditions to the user of the dishwasher appliance 100.

According to an exemplary embodiment, indicator zones 256 may correspond to user input buttons 166. In this regard, control panel 220 may include a plurality of capacitive sensors 258 which are mounted below selected indicator zones 256 and are operable to detect user inputs on overlay panel 150 of control panel 220. For example, a capacitive sensor 258 may be mounted to printed circuit board 230 and may be configured for triggering when a user touches a top surface 252 of overlay panel 250 proximate the capacitive sensor 258. In particular, capacitive sensors 258 can detect when a finger or another conductive material with a dielectric different than air contacts or approaches control panel 220.

When a user touches top surface 252 of overlay panel 250 adjacent one of capacitive sensors 258, such capacitive sensor 258 triggers and, e.g., signals a controller (e.g., controller 160). In such a manner, operations of dishwasher appliance 100 can be initiated and controlled. Capacitive sensors 258 may be distributed laterally on printed circuit board 230 below overlay panel 250. It will be understood that other any suitable number, type, and position of capacitive sensors 258 may be used while remaining within the scope of the present subject matter. Indeed, any suitable number, type, and configuration of touch buttons or user inputs 166 may be used while remaining within the scope of the present subject matter.

In general, console cover 240 and/or overlay panel 250 may be constructed from any suitably rigid material to facilitate operation of dishwasher appliance 100. For

11

example, it should be appreciated that various features of control panel 220 may be formed by injection molding, e.g., using a suitable plastic material, such as injection molding grade Polybutylene Terephthalate (PBT), Nylon 6, high impact polystyrene (HIPS), acrylonitrile butadiene styrene (ABS), or any other suitable blend of polymers. Alternatively, according to the exemplary embodiment, these components may be compression molded, e.g., using sheet molding compound (SMC) thermoset plastic or other thermoplastics. According to still other embodiments, portions of control panel 220 may be formed from any other suitable rigid material.

Referring now to FIG. 5, the assembly of control panel 220 will be described in more detail according to an example embodiment of the present subject matter. In this regard, as illustrated, control panel 220 may generally include a console bracket 260 that is positioned within door 116 for securing printed circuit board 230 and/or console cover 240. Specifically, according to the illustrated embodiment, console bracket 260 may generally extend along the transverse direction T between inner door panel 216 and outer door panel 218. Console bracket 260 may generally be formed from any suitably rigid material to provide structural rigidity to control panel 220 and for mounting control panel 220 into or on door 116.

As explained above, printed circuit boards are used in control panels for mounting and connecting various electronic components or circuits. Specifically, these components are commonly mounted in holes that pass through the printed circuit boards. In this regard, electrical contacts from the electronic components pass through the holes and are soldered or otherwise joined to a backside of the printed circuit boards. Notably, these soldered electrical connections may protrude slightly from the surface of the printed circuit boards and may create an interference when installed in tight assembly spaces. Aspects of the present subject matter are directed to compensating for or providing relief for these interferences.

In this regard, as shown in FIGS. 5 and 6, electronic components 262 are mounted to bottom surface 234 of printed circuit board 230. Electrical contacts 264 of those electronic components 262 pass through a through hole 266 that passes through printed circuit board 230 from the top surface 232 to bottom surface 234. Electronic components 262 are then secured to printed circuit board 230 by forming one or more soldered joints 268 on top surface 232 of printed circuit board 230 to fix electrical contacts 264.

However, as best shown in FIG. 5, printed circuit board 230 is seated directly against console cover 240, creating the potential for interference between soldered joints 268 and console cover 240. As described herein and illustrated in FIGS. 6 through 11, aspects of the present subject matter are directed to structures and methods for providing relief for such soldered joints 268 or similar electrical connections or components. Although joints 268 are described herein as being soldered, it should be appreciated that aspects of the present subject matter may apply to any other suitable electronic joint or connection.

As illustrated, control panel 220 may further include one or more standoff features 270 that are positioned between console cover 240 and printed circuit board 230 to create a localized gap 272 between console cover 240 and printed circuit board 230. In this regard, standoff features 270 may be generally designed to create separation between console cover 240 and printed circuit board 230 to provide relief for receiving soldered joints 268. Although exemplary standoff features 270 are illustrated and described herein, it should be

12

appreciated that other standoff features are possible and within the scope of the present subject matter.

While it may be desirable to create localized gap 272 near connections where electronic components 262 are mounted to printed circuit board 230, it may also be desirable to have a firm or close contact engagement or flat interface between console cover 240 and printed circuit board 230 at other locations. For example, the effective performance of lights, capacitive sensors, and other electronic components may require that printed circuit board 230 be seated directly against console cover 240. Accordingly, the localized gaps 272 contemplated herein may be positioned only where necessary for providing relief for soldered joints 268.

According to the illustrated embodiments, standoff features 270 are illustrated as extending from console cover 240 toward the top surface 232 of printed circuit board 230. However, it should be appreciated that according to alternative embodiments, standoff features 270 may be formed directly on or attached to printed circuit board 232 and may extend out toward console cover 240. Indeed, any suitable feature positioned between printed circuit board 230 and console cover 240 may be used to create the desired localized gap 272.

It should be appreciated that any suitable number, size, and geometry of standoff features 270 may be used while remaining within the scope of the present subject matter. For example, according to the embodiment illustrated in FIGS. 7 through 9, console cover 240 includes four standoff features 270 that are spaced apart to form a rectangle on console cover. In general, the interior of this rectangle may be referred to as the electronics mounting area 274 and may serve as a dedicated region within control panel 220 where some or all electrical connections are established and soldered joints 268 are located.

As shown, the standoff features 270 shown in FIGS. 7 through 9 have a substantially circular cross section. By contrast, according to the embodiment illustrated in FIGS. 10 and 11, standoff features 270 may be rectangular protrusions. Standoff features 270 may have other suitable sizes, positions, geometries, and orientations while remaining within the scope of the present subject matter.

In addition, according to an example embodiment, standoff features 270 may define a contact surface 276 on a distal end of standoff feature 270 that is angled to reduce stresses on printed circuit board 230 when mounted. Specifically, according to the illustrated embodiment, a cover direction 278 may be defined as extending in a plane or direction corresponding to the top surface 232 of printed circuit board 230, e.g., in a direction perpendicular to display direction 222. Contact surface 276 may define a surface angle 280 measured relative to cover direction 278. According to exemplary embodiments, surface angle 280 may be between about 0° and 30°, between about 1° and 20°, between about 2° and 10°, or about 5°. Other suitable angles and contact surfaces 276 are possible and within the scope of the present subject matter.

In addition, standoff features 270 may generally define a standoff height 282 measured along the display direction 222. In general, standoff height 282 may be selected to provide sufficient relief for soldered joints 268. For example, according to an exemplary embodiment, standoff height 282 may be between about 0.01 inches and 1 inch, between about 0.01 inches and 0.25 inches, between about 0.02 inches and 0.1 inches, or about 0.03 inches.

Notably, standoff features 270 create separation between printed circuit board 230 and console cover 240. However, it may be desirable to eliminate this separation at certain

13

locations on the board and to properly secure printed circuit board 230 to console cover 240. Accordingly, control panel 220 may further include one or more of retention features 284 that engage printed circuit board 230 to secure printed circuit board 230 to console cover 240. Specifically, according to the illustrated embodiment, retention features 284 may generally contact bottom surface 234 of printed circuit board 230 to retain or clamp printed circuit board 230 against control console cover 240 or against standoff features 270.

According to the illustrated embodiments shown in FIGS. 6 through 11, retention features 284 are defined on and extend from console cover 240. In this regard, the various retention features 284 may wrap around the edges or pass through printed circuit board 230 to secure it to console cover 240. By contrast, as illustrated for example in FIG. 5, one or more retention features 284 may be defined on or extend from console bracket 260.

According to an example embodiment, retention features 284 may generally be positioned proximate to standoff features 270, e.g., to secure printed circuit board 230 where it is not in contact with console cover 240 and/or to reduce stress due to bending of printed circuit board 230 where it is pushed away from console cover 240. For example, retention features 284 may be defined on an opposite side of standoff features 270 relative to electronics mounting area 274 or localized gap 272.

In general, retention features 284 may have any suitable geometry and attachment mechanism for engaging printed circuit board 230. For example, retention features 284 may include one or more of a clip, a snap, a hook, a flexible detent, a biased latch, or any other suitable mechanism. Example retention features 284 are shown in FIGS. 6 through 11, though one of ordinary skill in the art would understand that these are non-limiting examples, and any other suitable retention feature may be used.

In general, retention features 284 may include flexible clips that are positioned around an edge of printed circuit board 230. According to still other embodiments, as illustrated for example in FIG. 6, printed circuit board 230 may define a retention aperture 286 that extends through printed circuit board 230. According to example embodiments, one or more retention features 284 may pass through retention aperture 286 to engage bottom surface 234 printed circuit board 230. Other suitable retention features 284 and methods for engaging printed circuit board 230 are possible and within the scope of the present subject matter.

As explained above, aspects of the present subject matter are generally directed to a system and method for mounting a printed circuit board (PCB) to a casing without the necessity of creating a recess to accommodate through hole connector protrusions. A combination of mechanical features may be used to deflect the board to minimize or remove the need for the recess thereby improving the appearance of the part and still allowing for through hole connectors. The solution may include providing standoffs on console cover to set the spacing required to clear the connector leads and adding either flexible snap features or rigid hooks or a combination to pinch the outside edge and the inside edge of the board to lock in the required bend of the board while preventing stress from propagating further down the board. The hold down/retention features could be snaps or hooks from the cover itself or alternatively having the mating console bracket to push on the board directly.

This written description uses examples to disclose the invention, including the best mode, and also to enable any person skilled in the art to practice the invention, including

14

making and using any devices or systems and performing any incorporated methods. The patentable scope of the invention is defined by the claims, and may include other examples that occur to those skilled in the art. Such other examples are intended to be within the scope of the claims if they include structural elements that do not differ from the literal language of the claims, or if they include equivalent structural elements with insubstantial differences from the literal languages of the claims.

10. What is claimed is:

1. A control panel for an appliance, the control panel defining a display direction and comprising:

a printed circuit board defining a first surface, a second surface opposite the first surface along the display direction, and a through hole passing through the printed circuit board from the first surface to the second surface;

a console cover mounted to the first surface of the printed circuit board;

a standoff feature positioned between the console cover and the printed circuit board to create a localized gap between the console cover and the printed circuit board, wherein the standoff feature defines a contact surface that is angled in a non-parallel direction relative to a cover direction, the cover direction being perpendicular to the display direction;

a retention feature that engages the second surface to retain the printed circuit board against the console cover; and

an electronic component mounted to the printed circuit board and having an electrical contact that extends through the through hole, wherein a distal end of the electrical contact forms a connection joint that is positioned within the localized gap between the printed circuit board and the console cover.

2. The control panel of claim 1, wherein the retention feature is defined proximate to the standoff feature and on an opposite side of the standoff feature relative to the localized gap.

3. The control panel of claim 1, wherein the standoff feature is defined by and protrudes from the console cover toward the printed circuit board and contacts the first surface to create the localized gap between the console cover and the printed circuit board.

4. The control panel of claim 1, wherein the standoff feature is defined by and protrudes from the printed circuit board toward the console cover to create the localized gap between the console cover and the printed circuit board.

5. The control panel of claim 1, wherein the retention feature is a flexible clip that engages an edge of the printed circuit board.

6. The control panel of claim 1, wherein the printed circuit board defines a retention aperture, and wherein the retention feature passes through the retention aperture to engage the second surface of the printed circuit board.

7. The control panel of claim 1, wherein the standoff feature is one of a plurality of standoff features and the retention feature is one of a plurality of retention features.

8. The control panel of claim 7, wherein each of the plurality of retention features are defined outside of the plurality of standoff features relative to the localized gap.

9. The control panel of claim 1, wherein the standoff feature defines a standoff height measured along the display direction, the standoff height being between about 0.01 inches and 0.25 inches.

10. The control panel of claim 9, wherein the standoff height is about 0.03 inches.

15

11. The control panel of claim 1, wherein the retention feature is defined by the console cover and protrudes from the console cover toward the printed circuit board to contact the second surface to retain the printed circuit board.

12. The control panel of claim 1, further comprising: a console bracket, wherein the printed circuit board and the console cover are mounted to the console bracket, and wherein the console bracket defines the retention feature that contacts the second surface to retain the printed circuit board.

13. The control panel of claim 1, wherein the console cover comprises:

a plurality of user input zones; and a plurality of capacitive sensors mounted to the printed circuit board outside of the localized gap, the capacitive sensors being operable to detect user inputs via contact with the console cover in the plurality of user input zones.

14. The control panel of claim 1, wherein the control panel is mounted on a front panel or a top edge of a door of a dishwasher appliance.

15. A dishwasher appliance defining a vertical direction, a lateral direction, and a transverse direction, the dishwasher appliance comprising:

a wash tub positioned within a cabinet and defining a wash chamber;

a door pivotally mounted to the cabinet to provide selective access to the wash chamber; and

a control panel mounted on the door and defining a display direction, the control panel comprising:

a printed circuit board defining a first surface, a second surface opposite the first surface along the display direction, and a through hole passing through the printed circuit board from the first surface to the second surface;

5

10

20

15

25

30

16

a console cover mounted to the first surface of the printed circuit board;

a standoff feature positioned between the console cover and the printed circuit board to create a localized gap between the console cover and the printed circuit board, wherein the standoff feature defines a contact surface that is angled in a non-parallel direction relative to a cover direction, the cover direction being perpendicular to the display direction;

a retention feature that engages the second surface to retain the printed circuit board against the console cover; and

an electronic component mounted to the printed circuit board and having an electrical contact that extends through the through hole, wherein a distal end of the electrical contact forms a connection joint that is positioned within the localized gap between the printed circuit board and the console cover.

16. The dishwasher appliance of claim 15, wherein the retention feature is defined proximate to the standoff feature and on an opposite side of the standoff feature relative to the localized gap.

17. The dishwasher appliance of claim 15, wherein the standoff feature is defined by and protrudes from the console cover toward the printed circuit board and contacts the first surface to create the localized gap between the console cover and the printed circuit board.

18. The dishwasher appliance of claim 15, wherein the retention feature is defined by the console cover and protrudes from the console cover toward the printed circuit board to contact the second surface to retain the printed circuit board.
